UNITED STATES PATENT OFFICE.

AARON INNIS, OF POUGHKEEPSIE, NEW YORK.

DYE-WOOD CHIPPER.

SPECIFICATION forming part of Letters Patent No. 233,764, dated October 26, 1880.

Application filed April 10, 1880. (No model.)

To all whom it may concern:

Be it known that I, AARON INNIS, of Poughkeepsie, in the county of Dutchess and State of New York, have invented a new and useful Improvement in Dye-Wood Chippers, of which the following is a specification.

Figure 1 is a side elevation, partly in section, of the improvement. Fig. 2 is a front elevation, partly in section. Fig. 3 is a section 10 taken through the line x x , Fig. 2.

Similar letters of reference indicate corresponding parts.

The object of this invention is to furnish machines for cutting dye-wood into chips for making extracts and for grinding, which shall 15 be so constructed as to do the work rapidly and uniformly.

The invention consists in the particular means hereinafter described for securing the 20 knives of dye-wood chippers firmly in place, as hereinafter specified.

A is a shaft, which revolves in suitable bearings, and is provided with a fast pulley, B, and a loose pulley, C, to receive the driving 25 belt.

To the shaft A is attached a wheel, D, in the face of which is formed a V-shaped groove having slots E formed in its sides and alternating with each other to receive the knives 30 or cutters F.

The slots E may be radial, but I prefer to make them inclined, as shown in Fig. 1, so that the knives F may do their work with a drawing cut, and thus work easier.

The knives F are placed in the slots E, resting 35 against the shell of the wheel at the rear sides of the slots E and against ribs or projections G attached to or formed upon the outer side of the said shell, where the said

knives F are secured in place by a cross-bar, 40 H. The cross-bars H rest against the forward side of the rear part of the knives F, and have inclined lugs I formed upon their ends to rest against the sides of the body and rim of the wheel D, as shown in Figs. 2 and 3, so 45 that the screws passed through the said lugs I and screwed into the wheel D may draw the cross-bars H snugly against the knives F, and thus hold them firmly in place.

The wood to be chipped is laid in a V-shaped 50 feed-trough, J, and is designed to be fed forward to the cutting-wheel by a follower operated by a rack and pinion or other suitable feed mechanism. The feed mechanism is not shown in the drawings.

The forward end of the feed-trough J is tapered 55 to correspond with the groove of the cutting-wheel D, so that the wood may be firmly held while being cut. With this construction the dye-wood is cut rapidly into chips 60 of suitable size, to be used for making extract, or to be ground when it is desired to reduce the wood to a powder.

Having thus described my invention, I claim 65 as new and desire to secure by Letters Patent—

In a dye-wood chipper, the combination, with the slotted inclined sides of the V-shaped face of the cutting-wheel D, of the ribs or projections G and the fastening-bars H, having 70 inclined lugs I upon their ends, substantially as herein shown and described, whereby the knives F will be firmly secured in place, as set forth.

AARON INNIS.
